US0D1059330S

(12) **United States Design Patent** (10) **Patent No.:** **US D1,059,330 S**
(45) **Date of Patent:** **** Jan. 28, 2025**

(54) **REMOTE CONTROL**

- (71) Applicant: **Apple Inc.**, Cupertino, CA (US)
- (72) Inventors: **Jody Akana**, Los Altos Hills, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)

- (73) Assignee: **Apple Inc.**, Cupertino, CA (US)

- (**) Term: **15 Years**

- (21) Appl. No.: **29/930,870**

- (22) Filed: **Mar. 4, 2024**

Related U.S. Application Data

- (60) Continuation of application No. 29/835,283, filed on Apr. 18, 2022, now Pat. No. Des. 1,018,011, which is a continuation of application No. 29/674,636, filed on Dec. 21, 2018, now Pat. No. Des. 967,800, which is a continuation of application No. 29/485,556, filed on Mar. 20, 2014, now Pat. No. Des. 836,612, which is a continuation of application No. 29/432,443, filed on Oct. 15, 2012, now Pat. No. Des. 704,167, which is a continuation of application No. 29/404,056, filed on Oct. 14, 2011, now Pat. No. Des. 669,452, which is a continuation of application No. 29/391,544, filed on

May 10, 2011, now Pat. No. Des. 649,138, which is a continuation of application No. 29/366,344, filed on Jul. 23, 2010, now Pat. No. Des. 642,161, which is a division of application No. 29/345,286, filed on Oct. 13, 2009, now Pat. No. Des. 620,456.
